ATTORNEY

UNITED STATES PATENT OFFICE.

EUGENE RYNEARSON, OF DALLAS, TEXAS.

LOCK FOR METER BOXES.

Application filed January 29, 1921. Serial No. 440,892.

To all whom it may concern:

Be it known that I, EUGENE RYNEARSON, a citizen of the United States, residing at Dallas, in the county of Dallas and State 5 of Texas, have invented certain new and useful Improvements in Locks for Meter Boxes, of which the following is a specification.

This invention relates to meter boxes and 10 has for its object to provide certain improvements over Letters Patent No. 1,092,400 granted to me April 7, 1914, such improvements residing in a new and more positive and effectual manner of operating the sliding bolt or locking member of the lock on 15 the cover of the box, and further to provide a means adapted to prevent the lock from being operated, or "picked" without the use of the proper key.

20 These and other minor advantages over the old form of lock will become apparent as the description of the invention progresses, reference being had to the accompanying drawings forming part hereof, in 25 which—

Figure 1 is a top view of the meter box with the cover in place and partly broken away.

Figure 2 is a perspective view of the key 30 for locking and lifting the cover.

Figure 3 is a fragmentary view in vertical section of the upper portion of the meter box and cover, showing the locking arrangement, the view taken on line 3—3 of Figure 35 4.

Figure 4 is a bottom view of the cover and locking arrangement.

Figures 5 and 6 are detail views of the locking arrangement, illustrating the bolt of 40 the lock in closed and open position, respectively.

Figure 7 is a cross-sectional view of the cover and lock taken on line 7—7 of Figure 4, the cover partly broken away, and

45 Figures 8 and 9 are minor detail views.

Referring more particularly to the drawings, 1 denotes the upper portion of the meter box provided with a ring 2 which has the inner flange 3 for supporting the 50 cover 4.

The cover 4 upon the underside of which is arranged the locking arrangement has a diametral rib 5 and two smaller ribs 6—6. A lug 7 projects outwardly from the under side of the cover and is bent outwardly and 55 forms a recess to receive the flange 3 when the cover is in place. Another lug 8 on the opposite side of the cover has an opening to receive a bolt 9, the opposite end of which bolt is seated in the center of the diametral rib 5.

Integrally formed in the bolt about the center thereof is a loop 11 on the front side of which and extending along one side of the bolt is a projection 12 which serves as a 60 stop and regulates the distance for the outward extension of the bolt head which is shown in closed position in Figures 3, 4 and 5, and in open position in Figure 6. A spring 13 has one end seated in the face 70 of the diametral rib 5, its opposite end being attached to the bolt 9. Lugs 10—10 prevent the bolt from rotating.

A key 14 is provided and has a lug 15 slightly bent or curved to engage the inside 75 of the loop 11. In Figure 5 the key is shown inserted through the key hole 16 in the cover 4, the lug 15 of the key resting against the loop 11. Turning the key will, by bearing against the loop, throw the bolt 9 backward 80 against the tension of the spring 13, see Figure 6. In this position the lug 15 rests in one corner of the loop and prevents the bolt from sliding back. The key is used 85 while in this position to lift the cover.

To prevent the bolt 9 from being "picked" or operated by unauthorized persons there is provided a semi-circular flange 17 adjacent the key hole which extends outwardly about half way of the width of the loop 11, see 90 Figures 4 and 7. Thus an instrument inserted through the key hole 16 is prevented from effectually bearing against the loop 11 to release the bolt.

Having thus described the nature and objects of the invention, what I claim as new and desire to secure by Letters Patent, is—

In a lock for meter boxes, in combination with the cover, comprising a bolt, a main rib on the underside of the cover, a lug op- 100

posite the rib, an aperture in the lug and rib to slidably receive the bolt, said bolt having a loop-like formation at approximately its center with an opening to receive 5 a key, a key hole registering with said opening in the loop-like formation, a spring having one end seated in the rib and its opposite end attached to said bolt, and a projec-
tion adjacent the key hole on the underside of the cover to prevent movement of the 10 bolt without the use of the key, and means on the cover to prevent rotation of the bolt.

In testimony whereof I have signed my name to this specification.

EUGENE RYNEARSON.
